Des. 177,353
Patented Apr. 3, 1956

177,353

FISH LURE

Walter S. Szczesniak, Detroit, Mich.

Application June 29, 1953, Serial No. 25,712

Term of patent 14 years

(Cl. D31—4)

Fig. 1

Fig. 2

Fig. 3

Fig. 4

Figure 1 is a perspective view of a fish lure, showing my new design;

Figure 2 is a side elevational view thereof;

Figure 3 is a front end elevational view; and

Figure 4 is a top plan view of the same.

I claim:

The ornamental design for a fish lure, as shown.
